UNITED STATES PATENT OFFICE.

ROBERT J. MITCHELL, OF WASHINGTON, DISTRICT OF COLUMBIA, ASSIGNOR TO
MITCHELL MACHINE COMPANY, OF WASHINGTON, DISTRICT OF COLUMBIA, A
CORPORATION OF DELAWARE.

KEYBOARD FOR MAIL-DISTRIBUTING MACHINES.

Application filed May 23, 1919. Serial No. 300,378.

To all whom it may concern:

Be it known that I, ROBERT J. MITCHELL, a citizen of the United States, residing at Washington, District of Columbia, have invented new and useful Improvements in a Keyboard for Mail-Distributing Machines, of which the following is a specification.

This invention relates to mail distributing or assorting machines, wherein letters or other pieces of mail or similar matter are taken from a common source and selectively distributed in accordance with their addressed destinations to a plurality of points or receptacles.

15 The invention relates more particularly to a keyboard for such machines. In a co-pending application, Serial No. 221,528, filed March 9, 1918, in which I appear as co-inventor, there is disclosed a mail distributing machine with which the key-board of this application is especially adapted to be used. It should be understood, however, that my improved key-board is of general application and is designed for use with all distributing machines.

Under the present system, the routing and distribution of mail is carried out by operators or distributors, who stand before a letter case having a number of boxes and 30 with the letters held in one hand with the addresses facing upwardly the operator takes the letters singly and after reading their addresses places them in their respective pigeonholes corresponding to their destinations.

As described in my prior application, the letters first undergo what is known in the postal service as the "primary separation", that is, the letters for the foreign countries, 40 the several States of the United States and large cities of the world are placed in their respective pigeonholes without reference to the routes by which they reach their destination. The packages of letters for the foreign countries and for those States not connected with the original office by more than one railway post office route are despatched without further handling. In this separation all letters having the same post office destinations are 45 at all times placed in the same receptacle or pigeon-hole, so that the only requirements on the part of the distributor in this separation is that he be able to read the different post office addresses. The "city packages"

are taken out and disposed of finally by the 55 original post office.

The remaining letters are those which have been divided into "State packages." Each of these packages of letters now undergoes a "final separation," which is required for the reason that, in these instances, two or more railway lines run from the original office through the State the mail of which is routed, and it is necessary that each line be given that portion only which 60 it or its connections can serve with greatest despatch. In finally separating the mail, packages are made up for the larger offices termed "direct." Where a number of offices are supplied through another office at a 70 junction point, the letters going to these offices so supplied are assorted together and delivered to the post office of the "direct" city which distributes them to the surrounding offices by star or rural routes or over 75 electric trains or the like.

The remainder of the mail for each State is assorted to be delivered to various railway post office routes passing through the particular State the mail of which is being 80 routed and which bear the names of the initial and terminal cities of the runs irrespective of the railroad or railroads which they travel.

It should here be pointed out, there is 85 called for in this "final separation" on the part of the distributor, a most thorough knowledge of the various railway routes, of the post offices along these routes, and of the train schedules for the several routes. 90 This fact will become more evident when it is recognized that at one time a letter for a given destination must be placed in one box along with the mail for other destinations, and at other times in another box 95 with mail addressed to different destinations. The disposition of the mail for a certain post office is dependent upon the time of day and the quickest route of delivery at that time, providing there are several routes by 100 which a letter may be sent to a given destination. On all occasions the operator must have in mind not only the train schedules over the different routes by which mail may be delivered to a given destination, but he must also know the names of the stations along each route, so that when he is to dispose of a letter for a certain office he may 105

immediately recognize the several routes that deliver to that point and also the one route which will deliver with the greatest despatch.

5 The above facts will become more evident from the following example which illustrates the final separation of mail in Washington, D. C., for a portion of the State of Virginia. The mail from Washington, 70
10 D. C., is distributed to the State of Virginia by two railroad lines, the Seaboard Air Line and the Southern Railroad, known as the Washington and Hamlet and Washington and Charlotte, respectively. The Southern 75
15 operates over a small portion of the former's track and then branches off to the west in the direction of Danville, Virginia, while the Seaboard continues on to Richmond. A train departs over the Washington and 80
20 Hamlet from Washington at nine-thirty p. m. for Richmond and the South, and all mail for delivery to post offices between Washington and Richmond is given to that train. The mail for the city of Richmond 85
25 and for the offices supplied through Richmond have during the "final separation," been collected into two separate bundles. The letters for the small towns which have 90
30 not sufficient population to warrant separate bundles, are collected into one or more mixed packages, and given to the railway post office clerk to distribute. This clerk immediately cuts these bundles and assorts the letters into pigeon-holes for delivery to the 95
35 local towns or offices along his route or for connecting lines. No other train departs from Washington over that line until three a. m. At eleven p. m. a train departs over the Washington and Charlotte, and this 100
40 train going south connects at Danville, Virginia, with a train going east to Richmond. Hence, after the nine-thirty Washington and Hamlet train departs and until the departure of the Washington and Charlotte 105
45 train, mail to Richmond and the surrounding district is given to the Danville and Richmond train which reaches Richmond prior to the arrival of the three a. m. train from Washington over the Washington and Hamlet Railway post-office. Now supposing 110
50 the Danville and Richmond train connects at Richmond with a train bound north for Washington leaving Richmond at three a. m. or the same time as the next south bound train leaves Washington, both traveling over the Washington and Hamlet tracks; the train from both Washington (south bound) and from Richmond (north bound) are 115
55 scheduled to meet at Fredericksburg en route. Then after nine-thirty p. m., the mail despatched from Washington is divided north and south of Fredericksburg, the latter portion being made up in a separate package and despatched to the Washington and Charlotte Railway post office having a 120
60 train leaving Washington at eleven p. m.
65

which transfers it to the Danville and Richmond train at Danville and the latter gives it to Washington and Hamlet (north bound) at Richmond for distribution and delivery. After that time all of the mail for Richmond and the post offices between Richmond and Washington is collected into a single package and despatched to the three a. m. train from Washington on the Washington and Hamlet line (south bound). It will be 75
70 noted that the mail to be distributed by the railway clerk between Washington and Richmond is during certain periods of time, collected by the original office into a single package and at other times it is divided into 80
85 two packages, each of which goes over different routes.

The above description of the present system of routing mail, which is also given in the specification of my prior application, 85
90 is herein repeated to emphasize this one fact—namely, that a most comprehensive knowledge of the various mail routes on the part of the operators is required. They depend upon their knowledge of the exact 95
95 location of every post office in every State, the various railroad lines leading to these post offices, and the train schedules of the routes, so as to determine the mail for the various stations that shall be associated in 100
100 a given box. For instance in the above example, at one time the mail for the stations north and south of Fredericksburg are placed in the same box—and at another time, since the mail for those stations north and the mail for those south are to go by different trains, this mail is placed in separate boxes. The operator must remember not only this, but he must quickly recognize the location of each post office so that as 105
105 soon as he receives a letter, say for Ashland, a station on the Washington and Hamlet south of Fredericksburg, he must immediately recognize the fact that mail for Ashland at all times goes in the box with the Daswell and Dunbarton mail (other stations south of Fredericksburg) and sometimes with the mail for Alexandria, Quantico, Woodbridge, Brooke, etc. (other stations between Washington and Richmond). 110
110

The above is an example of merely the character of knowledge a mail distributor must possess and as one distributor generally works for an entire State it should be evident that the above example must be multiplied many times in order to even approximate the knowledge a single distributor must possess. It should, further, be apparent that for one to obtain the knowledge required on the part of a mail distributor requires months of careful training and study which it is highly desirable to eliminate.

In my application above referred to there is disclosed a machine having a plurality of 130
135 tiers of receptacles and a delivery mecha-

nism for each tier, termed the final conveyor, which receives letters from a primary conveyor and upon the receipt of a letter automatically moves to the receptacle of its tier 5 to which the letter is to be delivered. There is adjacent each receptacle a selective stop which is actuated from a keyboard to cause the final conveyor to come to a stop in front of its given receptacle. In this machine 10 each key corresponds to given destinations and a certain receptacle, but in order to provide for "final separation" in which, as described above, mail that sometimes is sent to separate boxes is often sent to the same 15 box—there is provided plug mechanism which connects up a plurality of keys to the same stop for the "final conveyor" so that a plurality of keys may cause the delivery of mail to the same receptacle when this is 20 desirable.

In the prior application the keyboard comprises a plurality of keys, therein termed manipulative devices, each key having a push rod which, when the key is actuated, 25 moves a switch closing a circuit to put in motion the delivery mechanism and stops of the machine. The switch mechanisms of the machine are of standard number and size, and are all located within a box for which 30 the detachable keyboard serves as a cover.

It should be observed from a reading of the above that there is disclosed in my prior application a machine adapted to carry out a final separation of the mail. But in that 35 machine there is shown no keyboard which will eliminate the necessity for the operator to commit to memory the names of the various post offices whose mail is to be placed in the same box. While means is provided for causing mail, normally delivered to separate receptacles, to be delivered to the same receptacle there is indicated no specific arrangement for the keyboard or an arrangement permitting final separation of the 40 mail.

The present invention has as an object a 45 keyboard arrangement in which the individual keys have associated therewith the names of those post offices the mail for which at all times is delivered to the same receptacle.

It is the object of the present invention to provide a keyboard which will eliminate the necessity for the operator committing to memory the names of the normally associated 50 post offices and which will at the same time be adapted to fit upon the standard switch-box of the machine of my prior application. In other words, it is the aim of this invention to provide a keyboard arranged for the "final separation" of mail for a given area, the keys of the board having arranged in association therewith the names of given post offices along the mail routes of the area.

65 So far as I am aware, prior to my former

application, there was known no machine capable of "final separation" of mail because prior to that time there was no means known for causing a plurality of actuating keys to cause delivery to the same box. The 70 prior art does not disclose a keyboard which may be used with the standard switch or operating mechanism of such a machine and at the same time be arranged for the "final separation" of mail for a given area, by 75 having adjacent each key or on each key the names of post offices whose mail is always delivered to the same receptacle. The main difficulty in obtaining such keyboards has been the fact that while the keys of a board 80 will vary in size as regards each other, and while the corresponding keys of two boards which are arranged for "final separation" for two different areas will vary in size—the switch or operating box must necessarily 85 remain of the same standard size and construction. Furthermore, as is evident, a keyboard arranged for the "final separation", say for the States of Virginia and New York, will vary not only in the size of 90 the corresponding keys but also in the total number of keys.

A further object of my invention is to provide a keyboard such as is described above, having removable, interchangeable 95 keys so that the operator may place in conveniently reached position on the board those keys corresponding to destinations for 100 which there is a great deal of mail.

The above and other objects and features of my invention will become clear during the course of this description, reference being had to the accompanying drawings in which—

Fig. 1 is a sectional view of the upper portion of the operating or switch box of the machine of my prior application and a keyboard attached thereto.

Fig. 2 is a fragmentary view of a keyboard showing modified means for placing names adjacent the keys.

Fig. 3 is a vertical sectional view of one of the finger pieces of the keys shown in Fig. 1.

Fig. 4 is an elevational view of one of the 115 springs used for retracting the keys.

Fig. 5 is a detail view of a key, the base plate and spring being shown in section.

Fig. 6 is a top plan view of a portion of a keyboard.

Fig. 7 is a diagrammatic top plan view of 120 a keyboard of different outline from the form shown in Fig. 6.

Fig. 8 is a diagrammatic view showing a modified outline for a keyboard.

Referring to the drawings in more detail, 125 1 indicates a box or container for the operating mechanism of a distributing machine having located therein magnets 2 and switch levers 3 pivoted at 4 to suitable brackets (not shown). The bell-crank switch levers 130

are provided with suitable contacts (not shown) to make a circuit and throw into operation the delivery and stop mechanism of the machine. This feature is fully described in my prior application, and as the present invention relates merely to the keyboard it is unnecessary to further describe the operating mechanism of the machine.

Detachably secured to the box 1 by means of suitable latches 10 pivoted to the box is a keyboard comprising a base plate 9 having spaced openings above the switch levers 3 receiving push rods 8 and finger tips 7. The push rods 8 and their finger tips 7 constitute the keys of the board and are removably arranged in their respective openings for a purpose later to be described.

It should be observed that below the base plate 9 and slightly spaced therefrom is a guide plate 6 secured at its edges to the depending sides 5 of the base plate and having openings which register with the push rod openings of the base plate and serve as guides for the push rods.

The push rods are made square in cross section to prevent rotation and each passes through a similarly shaped opening 11 in a spider formed spring 12 the arms of which rest upon the base plate of the keyboard. The springs are slightly arched, as indicated in Fig. 5, so as to move the keys upwardly to inoperative position when the holding magnet 2 is de-energized, as described in my prior application.

The finger tips 7 of each of the keys may be formed so as to removably receive the name cards 13 (Fig. 3) in any suitable manner, but in the form of my device shown in the drawings I have provided each tip with upstanding flanges 7^a having lips 7^b thereon, the card being placed under the overturned lips in the usual manner.

Instead of placing the name-cards upon the keys, as shown in Fig. 3, these cards may be placed in spring clamps 14 located upon the base plate 9 between each of the keys. The entire keyboard may be rectangular in outline as shown in Fig. 6 or, if desired, be U-shaped as in Fig. 7.

The above describes the construction of a keyboard in which none of the finger tips must be of a size to overlap the opening in the base plate for an adjacent key.

It should be borne in mind that each key is to receive the names of those post offices in a given area which are always associated and whose mail is at all times to be delivered to the same receptacle. It is often found that a great many names must be located on the same key and that while one key will have thereon but one name, such as Richmond, as shown in Fig. 6, an adjacent key will have a plurality of names thereon. Due to the fact that the operating box should be of a standard size and con-

struction, and as the openings of the base plate register with the switch or operating levers a construction must be obtained which may be used upon a standard operating box and at the same time admit of rearrangement of the keys.

As shown in Fig. 1 those keys which must have tips of such a size as to cover the adjacent push rod opening in the base plate, while being provided with but one push rod, have short pins 15 which fit in the adjacent opening thereby providing a bearing for the key. A return spring for such a key may be located either between their pin and push rod (as shown) or around the push rod as in the case of the other keys.

It should be noted that the keyboard is made detachable so that after a "final separation" for one area is made it may be replaced by a keyboard arranged for the "final separation" of mail for another area, such as a State. Each keyboard is arranged for the "final separation" of mail for a given area, such as a State, by having located on each key the names of those post offices whose mail is always delivered to the same box. By putting on each key the names of the post offices, instead of the names of the routes, it is unnecessary for the operator to remember the names of the stations on each route or the time at which a letter for a given destination is to go by a certain route when the route by which it is delivered varies during the day. Taking the example used at the beginning of this description, the above will be made more clear. As shown in Fig. 6 which indicates the arrangement of a keyboard for a portion of the State of Virginia, as will be observed Danville and Richmond each have separate keys.

The key beneath the Danville key has upon it the names of Manassas, Orange, and Charlottesville, which are post offices between Washington and Danville on the Southern Railroad, or the Washington and Charlotte line. Mail for Manassas, Orange, and Charlottesville will always be placed in the same receptacle. Danville is placed upon a separate key because at certain times of the day, due to the train schedules, mail will reach Danville from Washington more quickly if it is sent by the Seaboard Air Line to Richmond and at Richmond placed upon a Richmond and Danville train, instead of being despatched on the Southern Railroad direct to Danville. At such times the Danville mail is delivered to the same receptacles as the mail for the stations between Richmond and Danville, namely, Moseley J'ct, Burkeville, Meherrin, and Keysville. At these times the plug is in my machine which will cause the Danville key and the key with the last mentioned names to deliver to the same receptacle.

From the above it will be clear that with my improved keyboard it is unnecessary for the operator to remember the names of the stations along each route, as these names are upon the keys. So far as I am aware, I am the first to provide a keyboard with the names of the post offices upon the keys, the names of the post offices whose mail is to be delivered at all times to the same receptacle being upon the same key, and the whole keyboard being thus arranged for the final separation of mail for a given area. The machines known in the art have keyboards adapted to have thereon only the names of States, etc. for "primary separation" or the names of mail routes if final separation is to be attempted, and in the latter instance the operator must know the names of the post offices along each route.

I would further emphasize the fact that in my keyboard the individual keys are removable and are also made interchangeable so that they may be transposed about the base-plate as desired. The importance of this feature in mail distributing machines can be pointed out in a few words. Taking the keyboard shown in Fig. 6, it will be observed that the Danville and Richmond keys, for instance, are located at the upper part of the keyboard. The indicated position for these is convenient for the operator that is separating the mail, say in Washington, where there is not a great deal of mail for delivery to these cities. But in a city where, in separating mail for Virginia, it is found that there is a relatively large quantity of mail for Danville and Richmond, it may be

desirable to position these keys in a more easily reached place upon the board. It is to make allowance for these necessities and changes in postal schedule, known as "scheme changes" in the postal service, that the keys are made interchangeable so that they may be transposed as desired. It is to be observed that instead of rearranging the keys, the name cards thereon could be transposed in cases where the keys of those cards to be transposed are of the same size, and on all occasions could this be done in the form of my invention shown in Fig. 2.

It should be understood that my invention is not limited to the specific form of keyboard shown in the accompanying drawings, wherein I disclose but one of many forms in which my invention might be embodied, but the true scope thereof is defined by the following claim.

I claim—

In a distributing machine having a plurality of adjacent operating members, a keyboard above said operating members comprising a base plate having a plurality of key openings therein above said operating members, keys provided with push rods extending through some of said openings and having guide pins of shorter length than said push rods extending through adjacent openings, said keys having finger tips with indicia thereon above the push rods and guide pins.

In testimony whereof I have hereunto set my hand.

ROBERT J. MITCHELL.
